UNITED STATES PATENT OFFICE

ARTHUR ORLOFF, OF GREEN BAY, WISCONSIN, ASSIGNOR TO NORTHWEST ENGINEERING CORPORATION, OF GREEN BAY, WISCONSIN, A CORPORATION OF WISCONSIN

TRENCH HOE

Application filed April 22, 1929. Serial No. 357,066.

The invention relates to excavators and more particularly those of the type usually called pull shovels, trench hoes or back diggers.

The usual types of pull shovels, wherein the hoist cable extends out to the outer end of the boom and over sheaves at the end of the boom or associated with the dipper stick so that said hoisting line and its sheaves get into the trench during digging, present a fruitful source of trouble inasmuch as it is impossible to keep dirt and grit from falling into the sheaves, with resultant troubles due to rapid wearing of the moving parts, particularly the cable, as when small stones get between the cable and the sheaves, cutting and consequent breakage are apt to result. According to the present invention these disadvantages are overcome by providing a hoisting cable separate from the dipper stick to raise and lower the boom and to utilize the tension of the hoist cable support to effect the operation of another cable which moves the dipper and its stick angularly relative to the boom.

A further object of this invention is to connect the shear leg cable with the dipper stick to effect the angular movement of the dipper relative to the boom through the tension set up in the shear leg supporting cables, the arrangement eliminating the necessity for sheaves at the forward end of the machine and permitting the use of a simple cable connection with the dipper stick.

The invention further consists in the several features hereinafter set forth and more particularly defined by claims at the conclusion hereof.

In the drawings Fig. 1 is an elevational view of an excavator embodying the invention. Fig. 2 is a detail plan view looking down on the inclined shear leg to show the arrangement of the cables.

Referring to the drawings the numeral 4 designates the traveling base of the machine equipped with endless propelling treads 5 driven in known manner from a suitable prime mover on the rotating base 6 of the machine, 7 a boom pivotally connected with the rotating base of the machine for up and down movements relative thereto, as by a pin

8, 9 the dipper handle or stick pivotally connected intermediate its ends by pin 10 to the outer end of the boom and carrying a dipper 11 facing toward the machine and equipped with digging teeth 12.

The usual drag cable 13 passes from the drag drum 14 over a pulley or sheave 15 on the boom 7 to a point of pivotal connection at 16 with the dipper, the winding in of the drag cable swinging the dipper and its handle inwardly toward the machine to effect a digging movement when the boom is lowered and in operative position relative to the trench and to effect the retention of the load in the dipper when the boom is in an elevated position.

For raising and lowering the boom, dipper and stick a hoisting cable 17 passes from the hoist drum 18 over a guide sheave 19 mounted on a pin 19' on a movable support or shear leg 20, thence around a sheave 21, mounted on the medial portion of the boom or back from its forward end and is dead ended at 22 upon the shear leg 20. Thus winding in on the hoisting cable raises the boom 7 and parts carried thereby and paying out of this cable lowers these parts.

The drums 14 and 18 are equipped as usual with brakes and clutches to control their operation.

The shear leg or dipper shifting cable 23 is suitably secured at one end to the machine, as by a dead end connection 24, and extends therefrom over a guide sheave 25, thence over a sheave 26 pivotally mounted on the pin 19' on the shear leg and thence down around a pulley 27 pivotally mounted on the lower portion of said shear leg and thence forwardly along the top of the boom to a pivotal dead end connection 28 near the upper portion of the dipper stick 9. The shear leg 20 is pivotally supported on the machine in any suitable manner, as by the pivot pin 8.

It is obvious that the weight of the boom 7, dipper 11 and dipper stick 9 and various parts connected therewith will normally cause a tension to be extended in the boom hoist cable 17 and as one end of this cable is associated with the shear leg 20 carrying the shear leg cable 23 that the tension in said hoist cable will, in turn, cause a tension to be 100

exerted in the cable 23 in order that the shear leg may be supported and that this tension in the cable 23 is further increased by the weight of the shear leg. If, with the boom, dipper stick and dipper in the solid line position shown, the brake on the drag drum 14 is released, the tensioned shear leg cable 23 will effect an outward swinging of the dipper and its stick with respect to the boom, as noted by the dotted line position, it being noted that under these conditions the shear leg 20 swings to the right about its pivotal mounting 8 until it occupies the dotted position shown, this movement causing an effective shortening of the length of the cable 23 between the sheave 27 and the end 28. The reverse of this operation, namely, the drawing in of drag cable 18 until the dipper and its stick again assume the full line position, will exert a tension in the cable 23 which acts on the shear leg 20 to restore it to its solid line position. From the foregoing it will be noted that I have provided a means for shifting the position of the bight effected by the shear leg in the cable 23 to thereby exert a pull on said cable to shift the dipper and its stick relative to the boom.

Thus the dipper and its stick swings outwardly or inwardly relative to the boom under the control of the drag line and the position of the boom, the dipper and its stick, to accomplish the digging or unloading operation, is also under the control of the hoist line, it being noted that when the dipper is in the dotted line position and lowered into the material to be excavated that pulling in on the drag line causes the dipper to dig through and scoop up its load of material, which is then raised on the raising of the boom and discharged either by swinging the dipper outwardly relative to the boom or by providing the dipper with a bottom dumping door, long well known in excavators, or by providing other forms of discharge which form no part of the present invention.

From the foregoing description it will be noted that I have provided a pull shovel construction in which the tensioning of the shear leg or hoist cable support is used to effect the movement of the shear leg cable, which is operatively connected to the dipper handle to effect shifting movements of the dipper and dipper stick.

I desire it to be understood that this invention is not to be limited to any particular form or arrangement of parts except insofar as such limitations are included in the claims.

What I claim as my invention is:

1. In an excavating machine, the combination with a boom mounted for up and down movements, a dipper handle pivotally mounted on the outer end portion of said boom and carrying a dipper working toward the machine during digging, a hoisting cable associated with the boom, and means, in-

cluding a movable hoisting cable support operatively connected with said dipper and dipper handle, for effecting shifting movements of the dipper and dipper handle relative to said boom under the tension and movement of said support. 70

2. In an excavating machine, the combination with a boom mounted for up and down movements, a dipper handle pivotally mounted on the outer end portion of said boom and carrying a dipper working toward the machine during digging, a hoisting cable associated with the boom, a movable shear leg and a cable supporting said shear leg and associated with said dipper handle for shifting the dipper outwardly relative to the boom during the cycle of operations of the machine. 75

3. In an excavating machine, the combination with a boom mounted for up and down movements, a dipper handle pivotally mounted on the outer end portion of the boom and carrying a dipper working toward the machine during digging, a hoisting cable associated with the boom, boom-supporting means including a movable shear leg associated with the hoisting cable, and a shear leg cable tensioned by said shear leg and connected to said dipper stick to shift the same on the shifting of said shear leg. 80

4. In an excavating machine, the combination with a boom mounted for up and down movements, a dipper handle pivotally mounted on the outer end portion of said boom and carrying a dipper working toward the machine during digging, a hoisting cable associated with the boom, means including a movable hoisting cable support for effecting outward shifting of the dipper relative to the boom under the tension of said support, and means opposing the outward shift of said dipper and for swinging it inwardly toward said boom. 100

5. In an excavating machine, the combination with a boom mounted for up and down movements, a dipper handle pivotally mounted on the outer end portion of said boom and carrying a dipper working toward the machine during digging, a hoisting cable associated with the boom, a shear leg cable associated with said dipper handle for shifting the dipper outwardly relative to the boom, a movable shear leg for tensioning said shear leg cable, and a separately controlled third cable opposing the outward shift of said dipper and for swinging it inwardly toward said boom. 110

6. In an excavating machine, the combination with a boom mounted for up and down movements, a dipper handle pivotally mounted on the outer end portion of said boom and carrying a dipper working toward the machine during digging, a hoisting cable associated with the boom, a movable shear 115

leg associated with said hoisting cable, a shear leg cable having a bight about said shear leg and connected to said dipper handle for shifting said dipper outwardly relative to the boom under the tension set up by said shear leg, and a separately controlled cable for opposing said outward shifting and for shifting said dipper inwardly toward the boom.

10 7. In an excavating machine, the combination with a boom mounted for up and down movements, a dipper handle pivotally mounted on the outer end portion of said boom and carrying a dipper working toward the machine during digging, a hoisting cable associated with the boom, a pivoted shear leg with which said hoisting cable is connected, spaced sheaves mounted on said shear leg, a cable extending from the machine around the upper of said sheaves and over the lower of said sheaves to the upper end of the dipper handle for shifting said dipper outwardly relative to the boom, and a separately controlled cable for opposing 25 said outward shifting and for shifting said dipper inwardly toward the boom.

In testimony whereof, I affix my signature.
ARTHUR ORLOFF.
